Howard Stover

UNITED STATES PATENT OFFICE.

ELWOOD B. AYRES, OF PHILADELPHIA, PENNSYLVANIA, ASSIGNOR TO THE PHILADELPHIA TEXTILE MACHINERY COMPANY, OF PHILADELPHIA, PENNSYLVANIA, A CORPORATION OF PENNSYLVANIA.

DRIER.

1,255,685.

Specification of Letters Patent.

Patented Feb. 5, 1918.

Application filed May 3, 1916. Serial No. 95,078.

To all whom it may concern:

Be it known that I, ELWOOD B. AYRES, a citizen of the United States, residing in Philadelphia, Pennsylvania, have invented 5 certain improvements in Driers, of which the following is a specification.

One object of my invention is to provide a drier for bricks and similar material where it is desired to hold the moisture in the first 10 drying chamber so as to prevent the drying of the outside of the brick before the interior is dried.

A further object of the invention is to utilize the waste heat from the kiln in the 15 drier and particularly in the final section of the drier.

These objects I attain in the following manner, reference being had to the accompanying drawings, in which:

20 Figure 1 is a diagrammatic plan view of my improved drier;

Fig. 2 is a side view;

Fig. 3 is an end view showing the curtain raised;

25 Fig. 4 is a plan view illustrating a modification of the invention in which overhead circulating fans are used;

Fig. 5 is a view of the drier illustrated in Fig. 4, and

30 Fig. 6 is an end view of the same.

Referring to Figs. 1 to 3, inclusive, 1 is the casing of the drier which may be of any form desired and may be in any number of sections. In the present instance, I have 35 shown it in three sections *a*, *b* and *c*. The several sections can be separated by curtains 2, which are adapted to rollers and which are lowered after the trucks are run into the driers, and the curtains can be 40 raised when it is desired to move the trucks forward in the chambers.

45 8 is a central drying chamber and 4, 4 are the heating chambers, one located at each side of the drying chamber, and in these heating chambers are coils of steam pipes, in the present instance, and circulating fans 6 are located in the partitions between the heating chambers and the drying chambers and are mounted on horizontal shafts 7. 50 driven, in the present instance, by longitudinal shafts 8, as clearly shown in Figs. 1 and 2, although the method of driving these fans may be modified without depart-

ing from the essential features of the invention.

55 There are two fans for each of the sections *a* and *b*, so as to circulate the heated air across the drying chamber of each section. The moisture from the bricks, in the present instance, is retained in the section *a* 60 so that the air in circulation is moist, hot air. The section *b* is identical with the section *a*, with the exception that there is an exhaust pipe 9 in which there is an exhaust fan 10 mounted on a driven shaft 11, driven 65 by any suitable power. As the moist air circulates in the section *b* a certain proportion is drawn off through the exhaust pipe 9 and the bricks, when they are ready to leave this section, are comparatively free 70 of moisture. They are then passed into the section *c*, which is the final drying chamber. This section is not provided with heating coils but is connected to a flue 12 leading from the kiln. The flue is connected to a 75 blower 13 which draws the waste heat from the kiln and forces it through the flues 14, which extend to each side of the drier, and communicate with the drier through the upright flues 15 which enter the chambers 16 80 through passages 17, and this hot air is forced across the drying chamber by the fans 18, which are mounted on horizontal shafts 19 driven by the same mechanism which drives the shaft 7. In the roof of the drying chamber 85 of the section *c* is an exhaust passage connecting with a flue 20. In this flue is a damper 21 and in the in-take flues are dampers 22, Fig. 3.

In order to allow fresh air to enter with 90 the gases from the hot air, or gases from the kiln, I provide a fresh air duct 23 having a damper 24, and this duct communicates with the flue from the kiln, on the kiln side of the blower, so that the fresh air is thoroughly 95 mixed with the hot air before it enters the flues 14.

By this construction, the bricks are subjected to moist, heated air in the first section of the kiln and to moist, heated air of a 100 lesser degree in the section *b*, where a certain amount of the moist air is removed by the exhaust fan, so that the moisture is held in the bricks to prevent the bricks drying on the outside before the interior is thoroughly 105 dried. When the bricks pass into the third

chamber they are subjected to dry heat, which completes the drying of the bricks so that, when they are delivered at the discharge end of the kiln, they are completely 5 dried.

The waste heat from the kiln is discharged from the kiln at about 500 degrees and the temperature is reduced by the admission of fresh air through the duct 23, as the heat in 10 the drier is not usually over 300 degrees, and may be much lower.

The dampers are preferably controlled by automatic damper regulators, which may be of any of the ordinary types.

15 In Figs. 4, 5, and 6, I have shown another modification in which the same action takes place, but, in this case, the flue 14^a communicates with the rear end only of the third section *c'* and horizontally arranged circulating fans are located above the drying chamber and these fans are mounted on vertical shafts, as clearly shown, doing away 20 with the side chambers. There are flues 25 under the floor of the drier through which 25 the air circulates and these flues communicate with vertical exhaust flues 26 provided with dampers 27 so that the air from the kiln after it passes through the section *c'* is exhausted through said exhaust flues. The 30 sections *a'* and *b'* have coils of steam pipes

5^a at the sides. Circulating fans circulate the air up through the heating chambers of the first section, down through the drying chamber in the said first section, then through a flue 28 in the floor of the structure 35 to the sections *b'*, the moist air finally exhausting through the flue 9^a in the roof of the structure and in this exhaust flue is a suitable damper.

I claim:

1. The combination in a drier, of a series of sections, each section having a drying chamber; means for supporting the material to be dried in the chambers of said sections; means for circulating the air in each of said 45 sections; a flue for conducting hot air to the last section; and a flue connecting with said section through which the moist air escapes.

2. The combination in a brick drier, of a structure having a series of sections therein; means for separating the sections; circulating fans for circulating air independently in the several sections; heating coils in the first section for heating the air circulated therein; a final section; means for admitting preheated air to said final section; and means for exhausting the moist air from said section so that the bricks are thoroughly dried when they leave the drier.

ELWOOD B. AYRES.
